(57) **CLAIM**

The ornamental design for an electric bicycle, as shown and described.

DESCRIPTION

FIG. 1 is a left side elevation view of an electric bicycle embodying my new design;
FIG. 2 is a right side elevation view thereof;
FIG. 3 is a front elevation view thereof;
FIG. 4 is a rear elevation view thereof;
FIG. 5 is a top plan view thereof;
FIG. 6 is a rear perspective view thereof; and,
FIG. 7 is a front perspective view thereof.

The broken lines in the drawings illustrate portions of the electric bicycle that form no part of the claimed design.
